UNITED STATES PATENT OFFICE

148,830

DESIGN FOR A MOTION PICTURE PROJECTOR

Mario C. Ubaldi, Chicago, Ill., assignor to Excel
Movie Products, Inc., a corporation of Illinois

Application June 16, 1947, Serial No. 139,712

Term of patent 14 years

(Cl. D61—1)

To all whom it may concern:

Be it known that I, Mario C. Ubaldi, a citizen of the United States, residing at Chicago, in the county of Cook and State of Illinois, have invented a new, original, and ornamental Design for a Motion Picture Projector, of which the following is a specification, reference being had to the accompanying drawing, forming part thereof. The essential features of my design are shown in full lines, the broken lines shown in Figs. 1 and 2 being omitted from Figs. 3 and 4 for convenience of illustration.

Figure 1 is a side elevational view of a motion picture projector embodying my design;

Figure 2 is a side elevational view of the same projector, looking from the side opposite to that shown in Figure 1;

Figure 3 is a front elevational view of the same projector; and

Figure 4 is a rear elevational view of the same projector.

I claim:

The ornamental design for a motion picture projector, as shown and described.

MARIO C. UBALDI.
